RAILWAY VEHICLE

Alfred W. Bruce, New York, N. Y., assignor to
 American Locomotive Company, New York,
 N. Y., a corporation of New York

Application December 26, 1935, Serial No. 56,157

9 Claims. (Cl. 105—82)

This invention relates to railway vehicles, and more particularly to axles therefor and springs supported by said axles for supporting the frame constructions of the vehicles.

5 The principal object of the invention is to provide a spring assembly carried by an axle as aforementioned including at least one leaf spring and at least two helical springs in "parallel" with the leaf spring, all of said springs being supported by an axle, in part or entirely through the intervention of a rigid beam forming part of the assembly, and supporting said frame construction through the intervention of hangers connected to said frame construction at their 10 lower end portions and supported at their upper portions, each by one of said helical springs and by said leaf spring at an end thereof.

15 Other objects of and advantages achieved by this invention will be apparent from the following description when considered in connection with the accompanying drawings.

In the accompanying drawings Figure 1 is a diagrammatic side elevation of a locomotive embodying the present invention applied to a rear truck axle of the locomotive; Fig. 2, at the right, is a side elevation and, at the left, a partial section on the line II—II of Fig. 3, of longitudinal halves of the spring assembly of the present invention shown in Fig. 1; Fig. 3, at the right, is an end view of a transverse half of Fig. 2 and, at the left, a section of a transverse half of Fig. 2 on the line III—III thereof, certain parts of the truck being shown in Figs. 2 and 3 in dot and dash lines; Fig. 4 is a diagrammatic side elevation of a locomotive embodying the present invention applied to a driving axle of the locomotive; Fig. 5, at the right, is a side elevation, and, at the left, a partial section on the line V—V of Fig. 6, of longitudinal halves of the spring assembly of the present invention shown in Fig. 4; and Fig. 6, at the right, is an end view of a transverse half of Fig. 5 and, at the left, a section of a transverse half of Fig. 5 on the line VI—VI thereof, certain parts of the locomotive being shown in Figs. 5 and 6 in dot and dash lines.

45 Referring more particularly to Figs. 1 to 3, the locomotive here shown diagrammatically is indicated generally by the reference numeral 1, and only parts thereof necessary for a clear understanding of the present invention will be specifically referred to.

The locomotive shown is of a conventional type, the well-known parts being merely indicated. It comprises a main frame 2, the usual jour-

nal boxes 3 housed for vertical movement in side members 4 of the frame 2, driving axles 5 supporting the respective journal boxes, driving wheels 6 carried by said axles, a trailing truck, indicated generally by the numeral 7, comprising a frame 8, swivelled at its front end to the frame 2 in the usual manner, which, together with the frame 2, provides the frame construction for the locomotive superstructure, journal boxes 9 housed for vertical movement in the frame 8, and a wheeled axle 10 supporting the journal boxes 9, the wheels of the axle 10 being disposed at the inner sides of the sides of the frame 8.

5 The locomotive further comprises at each side thereof a spring rigging, indicated generally by the numeral 11. The rigging (only one being shown and described) is of usual construction and comprises a leaf spring 12 mounted on each of the driving axle journal boxes 3 by means of a spring saddle 13, equalizing levers 14 disposed between adjacent ends of the springs 12, fulcrumed at 15 to the adjacent frame side member 4 and connected at their ends to the adjacent ends of the springs by hangers 16, a hanger 17 connected at its upper end to the front end of the foremost spring 12 and at its lower end to the adjacent frame side member 4, a hanger 18 connected at its upper end to the rear end of the rearmost spring 12, a lever 19 fulcrumed to the truck frame 8 at 20 and connected at its forward end to the lower end of the hanger 18, and a spring assembly which is an exemplification of the spring assembly 21 of the present invention, carried by the journal box 9, comprising the springs and certain associated parts, later to be described, and hangers 22 and 23, the hanger 22 being supported at its upper portion by the springs of the assembly 21 at the forward end thereof, and connected at its lower end to the rear end of the lever 19, and the hanger 23 being supported at its upper portion by the springs of the assembly 21 at the rear end thereof, and connected at its lower end to the truck frame 8. The frame 2 is supported upon the truck frame 8 at its rear end by the usual supporting means, indicated at 24.

Now describing in detail the embodiment of the spring assembly 21 of the present invention, shown more particularly in Figs. 2 and 3, it is 50 to be noted that this embodiment is shown in connection with the truck axle 10 only. It comprises a rigid beam 25 which is supported at its central portion by the journal box 9. A seat 26 is formed on the top of the journal box for this 55

purpose and a plate 27, secured to the beam by welding, has a rounded bottom surface which rests upon the seat 26, in coacting relation therewith, to permit slight tilting of the beam relative to the box in a vertical plane when necessary. The box is provided with upstanding flanges 28 overlapping opposite sides of the plate 27 to prevent horizontal longitudinal displacement of the beam.

10 The beam in this embodiment comprises a straight horizontal bottom plate 29 and is channel-shape in cross section, having upstanding strengthening side plates 30 providing a housing for the springs later to be described. The side 15 plates are relatively low at their end portions and increase in height from the respective end portions to the center, thereby providing great strength for the beam. The beam is further provided with strengthening end flanges 31 connected 20 to the bottom plate, and at their ends connected to the side plates. The beam is disposed between extensions 32—32 formed on the sides of the frame 8 which prevent horizontal transverse displacement of the beam.

25 A semi-elliptic leaf spring 33 is disposed at its central lower portion within the housing with its central portion spaced above the central portion of the plate 29. The spring comprises a series of 30 plates 34, in the main gradually decreasing in length from the top to the bottom and symmetrical at each side of the vertical transverse plane of the spring, thereby providing a bottom, the portions of which on each side of the center portion diverge upwardly towards the ends of the spring, providing 35 at each end a space of increased height between the end of the spring and the adjacent end of the plate 29. The spring is, in the main, of usual construction. It comprises a spring band 35 which is provided at its bottom face with a 40 cylindrical concave surface 36 extending in a direction transversely of the spring. A block 37, disposed below the band 35, is secured to the plate 29 by welding, and is provided at its top with a cylindrical concave surface 38 opposite the 45 cylindrical surface 36. A roller 39 is disposed between the two cylindrical surfaces, providing a seat for the spring 33 for support of the spring by the journal box, and providing for coaction of said surfaces to permit slight tilting of the 50 spring relative to the box in a vertical plane when necessary.

55 A spring seat 40 is formed on the plate 29 at each end thereof. A spring 41 of the helical type is supported on each of the seats 40. While a single helical spring or a compound helical spring of any of the various types may be employed at each end, in the present instance two helical springs are employed at each end, an inner helical spring 42 and an outer helical spring 43. A cap 44, 60 having a groove 45 formed on its upper face running in a direction transversely of the beam and a slot-like orifice 46 running in a direction longitudinally of the beam, is mounted on each of the springs 41. Each cap has a downwardly extending circular flange 47 encircling the spring 41 to aid in holding the spring in place.

70 The assembly 21 further comprises the hangers 22 and 23 before referred to. The spring 33 at each of its end portions is provided with a slot-like orifice 48 in line with the adjacent orifice 46, and a hanger clip 49 of usual construction having the usual depression for a gib and a slot-like orifice for a hanger is mounted upon the spring at each end with its orifice in line with the adjacent 75 orifices 46 and 48. A slot-like orifice 50 is pro-

vided in the plate 29 at each end thereof in line with the orifices adjacent thereto. The hanger 22 extends downwardly through the orifices and the spring 41 at the forward end of the spring assembly and has an upper end portion extending 5 above the adjacent clip 49. An orifice is formed in this upper end portion adjacent the depression in the adjacent clip 49 and engages a gib 51 of usual construction, which is seated at its end portions in the depression provided in the clip, whereby the hanger is supported by the spring 33. The hanger is formed with another orifice adjacent the groove 45 of the adjacent cap 44, and engages a gib 52 which is seated at its end portions in the groove 45, 15 whereby the hanger is supported by the spring 41 adjacent thereto.

10 The hanger 23 is mounted similarly to the hanger 22, extending downwardly through the orifices and the spring 41 at the rear end of the 20 spring assembly, and has an upper end portion extending above the adjacent clip 49. Orifices are formed in the hanger 23 similar to those formed in the hanger 22 for similar gibs 53, 54 which similarly respectively engage the clip 49 and cap 25 44 respectively adjacent thereto. The lower end portions of the hangers 22 and 23 may be secured in any suitable manner directly to the truck frame 8, or through intermediaries as the case 30 may require, for supporting the desired portion of the weight of the superstructure upon the axle 10. In the present instance, as before stated, the lower end portion of the hanger 22 is pivotally secured to the rear end of the lever 19, and the lower end portion of the hanger 23 is pivotally secured directly to the truck frame 8.

35 Referring now more particularly to the second embodiment of the invention shown in Figs. 4 to 6, here the spring assembly is designed principally for use in connection with driving axles. The 40 construction of the locomotive shown in Fig. 4 is, in the main, similar to that shown in Fig. 1. Therefore as to similar parts similar reference numerals are applied and these parts will require 45 no further description.

40 Coming now to the spring rigging, this, in general, is similar to that shown in Figs. 1 to 3 but the beam and hangers are somewhat different. The spring rigging is indicated generally by the reference numeral 11' and comprises spring assemblies 21', later more fully to be described, one disposed over each of the driving axles 5, the rigging including a plurality of hangers 16' and hangers 17' and 18', all connected at their upper portions in a manner similar to the hangers 22 50 and 23 of the first embodiment, and having connection at their lower end portions similar respectively to the hangers 16, 17 and 18 of said first embodiment, adjacent hangers 16' being pivotally connected at their lower end portions 55 to levers 14, hanger 17' being pivotally connected at its lower end portion directly to the frame side member 4, and hanger 18' being pivotally connected at its lower end portion to the forward end of the lever 19.

60 The truck 7 is similar to the truck of the first embodiment except instead of using a spring assembly of the present invention a usual type of semi-elliptic spring 55 is employed in supporting engagement with the journal box 9. The spring 70 55 is connected at its opposite ends to hangers 56, the forward hanger 56 being pivotally connected at its lower end to the rear end of the lever 19, and the rear hanger 56 being pivotally connected at its lower end directly to the frame 8. 75

Referring more particularly to the spring assembly '21' of this embodiment, this assembly differs very little from the assembly 21 and accordingly similar parts bear similar reference numerals and will require no further description. This spring assembly is designed particularly for mounting it upon the spring saddle of the journal box 3 of a driving axle 5. And in order to economize on vertical space, as the space in this particular location is often limited, the central portion of the beam 25' is considerably raised above the end portions of the beam to enable the beam to be mounted upon the saddle, which is of considerable height, without correspondingly raising the spring assembly as a whole, as would otherwise be the case if the bottom plate 29' were straight, as in the first embodiment. This bottom plate 29' accordingly comprises a raised seat-providing central portion 57, seat-providing end portions 58 disposed below the central portion 57 and wall portions 59 extending respectively from the opposite ends of the portion 57 downwardly to the inner end of the portion 58 adjacent thereto. To compensate for the raising of the central portion 57 the block 37' is given a correspondingly less height than the block 37.

The plate 27' seats upon the spring saddle 13'. The saddle is provided with upstanding flanges 28' overlapping two of the sides of the plate 27' oppositely disposed to each other, to hold the spring assembly against horizontal longitudinal movement, and the plate 27' at its other two sides is provided with downwardly projecting flanges 60 which engage shoulders 61 formed in the adjacent sides of the saddle to hold the spring assembly against horizontal transverse movement.

While in each embodiment only one side of the locomotive has been particularly described it will be understood that both sides of the locomotive are similar, and while the invention has been described in connection with a locomotive it will be understood that it is applicable, where appropriate, to other railway vehicles, and may be applied in the same locomotive to both the rear truck and the driving axles. Furthermore while a semi-elliptic leaf spring only has been shown and described it will be understood that the invention contemplates any appropriate type of support composed of a plurality of plate members as a substitute for the semi-elliptic leaf spring shown. Moreover while the hangers of the respective spring assemblies have been shown in supported engagement with both types of springs, it will be understood that initially, as in previous practice, only one type of spring may support the hangers, the hangers in such an instance coming into supported engagement by the other type of springs upon a predetermined amount of flexing of the first type and the claims are intended to cover this arrangement also. Also while only one leaf spring has been shown in the assembly the invention contemplates employing two or more springs, if desired, disposed side by side either supported upon the same beam or upon separate beams, and similarly while only one pair of helical springs is described others may be employed, if desired. In short various combinations of springs other than that shown is contemplated as within the spirit of the invention.

The beam has been described as providing three spring seats, but it is within the purview of the invention to support the leaf spring by the journal box without the intervention of the beam, an orifice being provided in the bottom plate of the

beam to permit such mounting, the beam being supported in such case by the journal box through engagement of the beam at its margin about the orifice and, unless otherwise particularly specified in the claims, the claims are intended to cover such an arrangement of seating means, that is to say, to cover seating means broadly regardless of the manner in which the axle supports the leaf spring and beam. Of course in any instance the beam will still be supported by the axle, and in the preferred embodiments the beam is constructed as shown and described, wherein the leaf spring is supported by the bottom plate, for in such construction the weight imposed upon the leaf spring serves to firmly hold the beam upon its seat.

It will therefore be understood that, while there have been hereinbefore described approved embodiments of this invention, many and various changes and modifications in form, arrangement of parts and details of construction thereof may be made without departing from the spirit of the invention and that all such changes and modifications as fall within the scope of the appended claims are contemplated as a part of this invention.

The invention claimed and desired to be secured by Letters Patent is:

1. In a railway vehicle, a wheeled axle; a load-supporting frame construction; a leaf spring having its central portion disposed over said axle; two helical springs disposed one at each end portion of said leaf spring in vertical alignment therewith; seating means, carried by said axle and supporting each of said springs, supporting said helical springs at the bottoms thereof and said leaf spring at the bottom thereof at its said central portion; and a hanger at each of said end portions of said leaf spring, extending through said helical spring adjacent thereto, supportingly connected at its lower end portion with said frame construction, and supportedly engaged by said springs, by supporting engagement of its upper portion by said adjacent helical spring at the top thereof and by supporting engagement by said end portion adjacent thereto of said leaf spring at the top thereof.

2. In a railway vehicle, a wheeled axle; a load-supporting frame construction; a leaf spring having its central portion disposed over said axle; two helical springs disposed one at each end portion of said leaf spring in vertical alignment therewith; seating means carried by said axle and supporting said leaf spring at the bottom of said central portion thereof and having at each end a seat supporting said helical spring adjacent thereto at the bottom thereof; and a hanger at each of said end portions of said leaf spring extending through said helical spring adjacent thereto and through said seat adjacent thereto, supportingly connected at its lower end portion with said frame construction, and supportedly engaged by said springs, by supporting engagement of its upper portion by said adjacent helical spring at the top thereof and by supporting engagement by said end portion adjacent thereto of said leaf spring at the top thereof.

3. In a railway vehicle, a wheeled axle; a load-supporting frame construction; a journal box supported by said axle; a lead spring having its central portion disposed over said axle; two helical springs disposed one at each end portion of said leaf spring in vertical alignment therewith; a rigid beam supported at its central portion by said journal box, said beam having at its said

- central portion a seat supporting said leaf spring at the bottom of its said central portion, and having at each end a seat supporting said helical spring adjacent thereto at the bottom of said adjacent helical spring; and hanger means at each of said end portions of said leaf spring, supportingly connected at its lower end portion with said frame construction, and supportedly engaged by said springs, by supporting engagement of its upper 5 portion by said adjacent helical spring at the top thereof and by supporting engagement by said end portion adjacent thereto of said leaf spring at the top thereof.
5. In a railway vehicle, a wheeled axle; a load- 10 supporting frame construction; a journal box supported by said axle; a rigid beam, channel-shape in transverse cross section, comprising a bottom plate and upstanding side plates providing a housing, said bottom plate being supported 15 at its central portion by said journal box and having a seat at its said central portion and a seat at each of its end portions; a leaf spring having its central lower portion disposed in said housing and supported by said central seat; a 20 helical spring at each end of said leaf spring having its lower portion disposed within said housing and supported by said end seat adjacent thereto; and hanger means at each end of said leaf spring, supportingly connected at its lower 25 end portion with said frame construction, and supportedly engaged by said springs, by supporting engagement of its upper portion by said adjacent helical spring at the top thereof and by supporting engagement by said end portion adjacent thereto of said leaf spring at the top thereof.
6. In a railway vehicle, a wheeled axle; a load- 30 supporting frame construction; a journal box supported by said axle; a rigid beam having its central portion disposed above and in spaced relation with said journal box; a leaf spring having its central portion disposed above and in spaced relation with said central portion of said beam; 35 a pair of coacting means within the first said space for supporting said beam by said journal box; a pair of coacting means within the second said space for supporting said spring upon said beam, said coacting means of at least one of said 40 pairs being adapted for rocking relative movement therebetween; a helical spring supported by said beam at each end thereof; and hanger means at each end of said leaf spring, supportingly connected at its lower end portion with said 45 frame construction, and supportedly engaged by said springs, by supporting engagement of its upper portion by said adjacent helical spring at the top thereof and by supporting engagement by said end portion adjacent thereto of said leaf 50 spring at the top thereof.
7. In a railway vehicle, a wheeled axle; a load- 55 supporting frame construction; a leaf spring having its central portion disposed over said axle and supported thereby; two helical compression 55 springs disposed one at each end portion of said leaf spring; seating means, carried by said axle and extending therebeyond at each side thereof to each of said helical springs affording a seat therefor for supporting same at the bottom thereof; and hanger means, one at each said end portion of said leaf spring, supportingly connected at its lower end portion with said frame construction, and supportedly engaged by said 65 springs, by supporting engagement of its upper portion by said adjacent helical spring at the top thereof and by supporting engagement by said end portion adjacent thereto of said leaf spring at the top thereof.
8. In a railway vehicle, a wheeled axle; a load- 60 supporting frame construction; a journal box supported by said axle; a rigid beam supported at its central portion by said journal box, having a seat at its central portion and at each of its end portions; a semi-elliptic leaf spring having 65 its central portion supported on said central seat and the portions of its bottom at the opposite sides of said central portion diverging upwardly, providing a space between each end of said spring and the adjacent end of said beam; a helical 70 spring supported on each of said end seats within
